Neil S. Weston,
his ATTORNEY

UNITED STATES PATENT OFFICE

WINTHROP K. HOWE, OF ROCHESTER, NEW YORK, ASSIGNOR TO GENERAL RAILWAY SIGNAL COMPANY, OF ROCHESTER, NEW YORK

SWITCH MACHINE FOR RAILROADS

Application filed August 16, 1929. Serial No. 386,307.

This invention relates to power operated switch machines, and more particularly to means for safe guarding the manual manipulation or "cranking" of such switch machines.

5 It is desirable to provide a suitable crank, or equivalent manual means, by which the mechanism of a power operated switch machine may be moved by hand, either because the machine is out of order, or for maintenance or adjustment; and it is also desirable to make provision so that the power must be cut off from the switch machine before the hand crank can be used. Such an arrangement is disclosed, for example, in my 10 prior Patent No. 1,466,903, dated September 4, 1923.

In accordance with the present invention, it is proposed to provide an automatic mechanical latch for the power cut-off device, 20 so that when the power cut-off device has once been actuated to crank the machine by hand, this device is mechanically latched in this position, and can only be released to again permit the application of power to the machine, by some authorized person, who 25 has a key to unlock the mechanism cover.

The characteristic features, functions and advantages of the invention will be in part apparent, and in part pointed out as the description progresses.

In the accompanying drawing, Fig. 1 shows a fragmentary plan view of an electrically operated switch machine of the type shown in my prior patent above mentioned; 35 Fig. 2 is a fragmentary transverse section on line 2—2 of Fig. 1, through the mechanism casing, showing the cover; Fig. 3 is a fragmentary section on line 3—3 of Fig. 1; Fig. 4 is a fragmentary view of the guard plate for the crank socket, shown in its operated position to permit the insertion of the crank; and Fig. 5 is a fragmentary section on the line 5—5 of Fig. 4.

In the specific construction of the electrically operated switch machine, shown in my prior Patent 1,466,903, and to which this invention has been shown applied, the gearing between the electric motor for the switch machine and the throw bar connected to the 45 switch points, includes a bevel gear 5 and a

shaft 6, provided with a socket 7 at the upper end to receive a suitable hand crank, so that the gearing may be turned by hand. To insert this hand crank (not shown), a hinged cap 8, covering an opening in the mechanism cover 9, is raised, and a guard plate 10 is shifted from the position shown in Fig. 1 to the position shown in Fig. 4, so that the opening 10^a in the guard plate 10 aligns with the crank socket 7. The guard plate 10 is 55 connected by a rod 11 to a contact 12, engaging a pair of insulated contact fingers 13, so that upon movement of the guard plate 10 said contacts are disengaged and the power circuit to the switch machine is broken.

This guard plate 10 is pivoted at 14, and on one side of the pivot is a recess 15 (see Fig. 3) to receive a spring pressed plunger 16, set in a hole in the cross brace 17. When the guard plate 10 is in the normal position 60 shown in Fig. 1, partly covering the crank socket and completing the power circuit, the spring plunger 16 engages in the recess 15 and holds the guard plate in this position, the upper end of said plunger 16 and said recess 15 being shaped to retain the guard plate 65 in this normal position against jar and vibration, but permitting manual shifting of the guard plate.

On the opposite side of the pivot 14 for the guard plate 10 is a hole 20, as shown in Fig. 5, adapted to receive the end of another spring pressed plunger 21 set in the cross brace 17. This other spring pressed plunger 21 engages the hole 20 when the guard plate 70 is shifted to the position shown in Fig. 4, permitting insertion of the crank and cutting off the power. The plunger 21 positively locks the guard plate 10 against movement, and can not be released, until some 75 authorized person unlocks and raises the cover 9, whereupon the plunger 21 may be pressed down to release the latch plate, by a suitable pin or other tool inserted through the small bore 20^a aligned with the hole 20.

85 From the foregoing, it will be apparent that this invention safe guards manual manipulation of power operated switch machines in a way to minimize the chances of 90 improper operation of the switch machine by 95 100

power to derail a train. For example, if the switch machine should get out of order, and it is necessary to crank it by hand to permit trains to move, power is cut off from the switch machine, and can not be restored except by an authorized person capable of assuming the necessary responsibility. Such an arrangement is desirable, because in practice it is sometimes necessary for someone to crank the switch machine who may not know just what to do under such circumstances, and may thoughtlessly put power back on the switch machine. After cranking it over, with the result that under certain combination of circumstances the switch may be thrown by power under a train. It is assumed that the authorized maintainer, having a key to unlock the cover, will not release the latch plunger 21 holding the guard plate 10 in the position to cut off power, until conditions are safe and proper to do so.

One specific embodiment of the invention has been illustrated and described in connection with a switch machine of one particular type; and it is evident that the specific construction disclosed is susceptible of modification and adaptation without departing from the invention.

What I claim is:—

- 30 1. In a switch machine, means permitting hand operation of the switch machine and including a movable member, power control contacts operated by movement of said member, and a spring actuated locking device for retaining said member in its operated position, said locking means being contained in a locked compartment and releasable only by an authorized person holding a key to said compartment.
- 40 2. In a power operated switch machine, a power cut-off switch, a manually operable member for operating the switch to cut off power, and locked means accessible only to an authorized person for holding said member in its actuated position to cut off the power.
- 50 3. In a switch machine of the character described, operating mechanism including a socket to receive a hand crank, a guard plate preventing insertion of the hand crank into said socket until said plate is shifted to an operated position, a circuit controller governing the application of power of the switch machine, said circuit controller being connected to said guard plate and opened by its movement to its operated position, and a spring engaged latch for locking said guard plate in its operated position, said latch being contained in a locked compartment.
- 60 4. In a switch machine of the character described, mechanism including a socket to receive a hand crank, a locked cover for the switch machine having opening therein through which the hand crank may be inserted into said socket, a guard plate accessible

through said opening and normally preventing insertion of said crank into said socket, a power circuit controller opened by the movement of said guard plate to an actuated position to permit insertion of the crank, and a spring engaged latch for locking said guard plate in its actuated position, said latch being accessible to disengage it only by an authorized person having a key for the locked cover.

In testimony whereof I affix my signature.

WINTHROP K. HOWE.
